UNITED STATES PATENT OFFICE.

OLLIE C. GEORGE, OF CRYSTAL LAKE, ILLINOIS.

DESIGN FOR AN ARBOR.

Application filed July 10, 1924. Serial No. 10,117. Term of patent 7 years.

To all whom it may concern:

Be it known that I, OLLIE C. GEORGE, a citizen of the United States, residing at Crystal Lake, in the county of McHenry and State of Illinois, have invented a new, original, and ornamental Design for an Arbor, of which the following is a specification, reference being had to the accompanying drawing, forming part thereof.

The figure is a perspective view of an arbor, showing my new design.

This arbor constitutes an article which is made and sold as an independent and complete article of garden or lawn furniture.

I claim:

The ornamental design for an arbor, as shown.

OLLIE C. GEORGE.
